UNITED STATES PATENT OFFICE

ANTHONY UTZ, OF HARTFORD, CONNECTICUT, ASSIGNOR TO ROYAL TYPEWRITER COMPANY, INC., OF NEW YORK, N. Y., A CORPORATION OF NEW YORK

AUTOMATIC RIBBON REVERSE

Application filed June 12, 1928. Serial No. 284,741.

This invention relates broadly to devices for reversing the feed of the ribbon when one spool is substantially empty. One of the objects of the invention is to provide such a ribbon reverse which will immediately function upon a single stroke of a key lever.

Another object of the invention is to provide a reversing mechanism which includes interponents which are alternately actuated by ribbon projections whereby said interponents are respectively moved to effective positions. Another object of the invention is to provide means for automatically returning the respective interponents to their initial positions immediately following the reversal of the ribbon travel. A further object of the invention lies in the provision of ribbon operated means for moving the interponents to effective positions, which means includes a lost motion connection for permitting the ribbon to feed a short distance after either interponent has been moved to its effective position and before the travel of the ribbon is actually reversed. Other objects will be apparent from the following detailed description and the appended claims.

Figure 1 is a front elevation of a ribbon mechanism showing the application of my invention.

Figure 2 is a horizontal sectional view thereof.

Figure 3 is an end elevation.

Figure 4 is a perspective view of the ribbon operated interponent mechanism, and

Figure 5 is a detail top plan view of one of the spools showing the ribbon, ribbon guide, and ribbon projection.

Although I have illustrated my invention in the accompanying drawings as being applied to a Royal portable typewriting machine, it will of course be understood that my invention is applicable to other types of machines.

In the drawings, the frame A supports the usual type bar segment B, and connected to this segment are brackets C-C which support the spool cups D. Journaled on the brackets C are vertically disposed spool shafts 5 and 6, and mounted on the upper ends of these shafts are ribbon spools 7 and 8,

respectively, to which a ribbon 9 is connected in the usual manner. Bearings 10-10 depend from the brackets C, and journaled on these bearings is a driving shaft 11. Fixed on one end of the shaft 11 is a beveled gear 12 which is adapted to mesh with a beveled gear 13 fixed on the lower end of the spool shaft 5. Fixed on the other end of the driving shaft 11 is a beveled gear 14 adapted to mesh with a beveled gear 15 fixed on the lower end of the other spool shaft 6. The driving shaft 11 is intermittently rotated and is capable of being moved longitudinally so as to be connected with one of the spool shafts and disconnected from the other. In order to rotate intermittently the driving shaft 11, said shaft is provided with a ratchet wheel 16 which is actuated by a pawl 17 pivoted as at 18 to a rocking frame 19. The rocking frame 19 is in the nature of a universal frame and includes the universal bar pivot rod 20. The frame 19 is actuated in the usual manner from any one of the key levers 21, one of such key levers only being shown.

In order to move automatically the driving shaft 11 longitudinally in either direction so as to couple and uncouple the respective spool shafts 5 and 6 whenever the ribbon travel reaches either end of its movement, I have provided the following mechanism:

Fixed to the driving shaft 11 are spaced grooved collars 22 and 23 respectively. Pivoted on the bracket C adjacent the collar 22 is a bell crank lever 24, one arm 25 thereof engaging in a groove of said collar 22. Pivoted on the frame C adjacent the collar 23 is a bell crank lever 26 having an arm 27 engageable in the groove of said collar 23. A pair of actuating arms 28 and 29 are fixed to the universal bar pivot rod 20 so as to oscillate therewith whenever a key is depressed. An interponent 30 is pivoted intermediate its ends as at 31 to the other arm 32 of the bell crank lever 24, and an interponent 33 is pivoted intermediate its ends as at 34 to the other arm 35 of the bell crank lever 26. These interponents swing about vertical axes and normally said interponents are in ineffective positions, viz., out of the paths of the actuating arms 28 and 29. Ribbon operat-

ing means are provided for alternately moving the interponents 30 and 33 into the paths of the respective actuating arms 28 and 29, whereby, upon depression of any key, either 5 of said arms 28 and 29 will cause the effectively moved interponent to rock its associated bell crank lever and thereby shift the driving shaft 11 longitudinally to uncouple and couple the respective spool shafts from 10 and to said main driving shaft. For this purpose I have provided a similar mechanism, and therefore the description of one only will be sufficient.

Each of these ribbon operated mechanisms 15 or means includes a ribbon guide 35' having an inclined side opening 36 for permitting the insertion or withdrawal of the ribbon from the guide. The location of the opening 36 serves to retain the ribbon within the 20 guide. The guide 35' is provided with a horizontal arm 37 which is formed with a longitudinal slot 38 for receiving a screw 39 mounted on the frame C and forming a sliding pivot for the guide. Pivottally mounted 25 on the arm 37 opposite the guide 35' is a bell crank lever 40, and to one arm 41 of said lever is pivottally connected a second bell crank lever 42. The horizontal arm 43 of the bell 30 crank lever 40 and the horizontal arm 44 of the bell crank lever 42 are connected by a coil spring 45. The arm 41 of the lever 40 is provided with a stop shoulder 46 for engaging the vertical arm 47 of the lever 42 so as to limit the swinging movements of said 35 pivottally connected levers in one direction. The lower end of the vertical arm 47 of the lever 42 is pivottally connected on the frame C, and a horizontal arm 48, which extends in the direction opposite the horizontal arm 44, 40 is connected to the frame C by a coil spring 49. Pivottally connected to a depending arm 50 of the lever 42 is a link 51 which is pivottally connected to the associated interponent 30 or 33.

45 Fixed to the ribbon at each end thereof is a projection 52 for actuating the ribbon guide 35' and consequently the associated interponent.

In order to retain the driving shaft 11 in 50 either of its extreme adjusted positions, I have provided a spring detent or latch 53 which is pivoted at one end, as at 54, to the bracket C. This latch is provided with spaced recesses 55 and 56 for alternately receiving a roller 57 mounted on an arm 58 fixed to the bell crank lever 24. The detent or latch 53 is yieldably retained in engagement with the roller 57 by means of a coil spring 59, which is connected at one end to 55 the detent and at its other end to the bracket C.

In operation as the ribbon becomes unwound from one spool, the projection 52 will engage the associated ribbon guide 35' and 60 cause said guide to be moved in a straight

line. This movement of the ribbon guide will, through the levers 40 and 42 and link 51, move the associated interponent into effective position, that is, in position to be engaged by the associated actuating arm, whereby, upon a single stroke of any key, the actuating arm will directly engage the interponent and thereby oscillate the associated bell crank lever. This movement of the bell crank lever will shift the driving shaft 11 longitudinally and thereby uncouple the driving connection between the driving shaft and the spool shaft of the spool which has just been wound, and couple the driving shaft with the other spool so as to cause the ribbon travel 70 to be reversed. This shifting movement of the driving shaft 11 will, through the bell crank lever 24, cause the arm 58 to be oscillated to engage either of the seats 55 or 56 of the detent 53 so as to retain the driving 75 shaft in its adjusted position. The interponents 30 and 33 are respectively provided with stop arms 60 and 61 which are adapted to respectively engage the sides of the actuating arms 28 and 29 and thereby retain the operated interponent in effective position. Just as soon as an interponent is moved to its effective position, the actuating arm will engage the same and immediately effect the ribbon reverse. Should a continued movement 80 be imparted to the ribbon guide after the interponent has been moved to its effective position, the loose connection formed by the pivoted levers 40 and 42, and the spring 45, will permit of the guide being thus moved without imparting any injury to the mechanism. After the ribbon has been reversed, the spring 49 will not only function to return the ribbon guide to its initial position, but will also 85 function to return the interponent to its initial or ineffective position.

I claim:

1. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillator actuating arms, a pair of interponents respectively pivoted on the levers and normally disposed out of the paths of movements of said actuating arms, and ribbon-controlled means associated with the respective spools for positively moving the interponents alternately into positions for engagements by the respective actuating arms.

2. A ribbon reversing mechanism for typewriters comprising in combination, spaced ribbon spool shafts, a longitudinally movable driving shaft normally connected to and disconnected from the respective spool shafts, key operated means for intermittently rotat-

ing said driving shaft, a pair of levers for respectively moving the driving shaft longitudinally in opposite directions, a universal rocking frame, a pair of oscillatory actuating arms fixed to the universal rocking frame, a pair of interponents respectively pivoted on the levers and normally disposed out of the path of movement of said actuating arms, and ribbon-controlled means associated with the respective spools for positively moving the interponents alternately into positions for engagement by the respective actuating arms.

3. A ribbon reversing mechanism for typewriters comprising in combination spaced ribbon spool shafts, a longitudinally movable driving shaft normally connected to and disconnected from the respective spool shafts, a ratchet mechanism for intermittently rotating said driving shaft and including a universal rocking frame, a pair of levers for respectively moving the driving shaft longitudinally in opposite directions, a pair of oscillatory actuating arms fixed to the universal rocking frame, a pair of interponents respectively pivoted on the levers and normally disposed out of the path of movement of said actuating arms, and ribbon-controlled means associated with the respective spools for positively moving the interponents alternately into position for engagement by the respective arms.

4. A ribbon reversing mechanism for typewriters comprising in combination, spaced ribbon spool shafts, a longitudinally movable driving shaft normally connected to and disconnected from the respective spool shafts, a pair of grooved collars fixed to the driving shaft, a pair of bell-crank levers for respectively moving the driving shaft in opposite directions, each lever having one arm engageable in the groove of one of said collars, a pair of oscillatory actuating arms, a pair of interponents respectively pivoted on the other arm of the bell-crank levers and normally disposed out of the path of movement of said actuating arms, and ribbon-controlled means associated with the respective spools for positively moving the interponents alternately into positions for engagement by the respective arms.

5. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms movable in planes at right angles to the longitudinal axis of the driving shaft, a pair of interponents respectively pivoted on the levers and normally disposed out of the path of movement of said

actuating arms, said interponents being movable in a plane at right angles to the general plane of oscillation of the actuating arms, and ribbon-controlled means associated with the respective spools for positively moving the interponents alternately into positions for engagement by the respective arms. 70

6. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, and separate means operated by ribbon projections for positively moving the interponents alternately into positions for engagements by the respective actuating arms. 80

7. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, and separate means operated by ribbon projections for positively moving the interponents alternately into positions for engagements by the respective actuating arms, said ribbon operated means including constant but yielding connections which permit the travel of the ribbon after the engagement of the associated interponents and actuating arms. 95

8. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, and separate means operated by ribbon projections for positively moving the interponents alternately into positions for engagements by the respective actuating arms, said ribbon operated means including means for automatically returning the associated interponent 110

from the path of movement of the actuating arm to its initial position subsequent to the ribbon travel being reversed.

9. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, and ribbon-controlled means associated with the respective spools for positively moving the interponents alternately into positions for engagements by the respective actuating arms, each interponent having a stop arm adapted for engagement with the side of the actuating arm to limit the effective movement of the interponent, said ribbon operated means including constant but yielding connections which permit the travel of the ribbon after the engagement of the associated interponents and actuating arms.

10. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, and ribbon-controlled means associated with the respective spools for alternately moving the interponents into positions for engagements by the respective actuating arms, said ribbon-controlled means including a ribbon actuated lever, a link connecting the lever and the interponent, and a spring connected to the lever for normally retaining the interponent in ineffective position.

11. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, and separate means operated by ribbon projections for positively moving the interponents

alternately into positions for engagements by the respective actuating arms, each of said separate ribbon operated means including a ribbon guide movable by the ribbon projection, and a single spring for retaining the guide and the associated interponent in normal position.

12. A ribbon reversing mechanism for typewriters comprising in combination, spaced ribbon spool shafts, a longitudinally movable driving shaft normally connected to and disconnected from the respective spool shafts, key operated means for intermittently rotating said driving shaft, a pair of levers for respectively moving the driving shaft longitudinally in opposite directions, a pair of oscillatory actuating arms, a pair of interponents respectively pivoted on the levers and normally disposed out of the paths of movements of said actuating arms, ribbon-controlled means associated with the respective spools for positively moving the interponents alternately in positions for engagements by the respective actuating arms, and a spring actuated latch cooperating with one of the levers for retaining the driving shaft in either of its longitudinally adjusted positions.

13. Ribbon reversing mechanism for typewriting machines including a frame, a ribbon spool shaft, normally disconnected operating means therefor, a slidable ribbon guide actuated by a projection on the ribbon, and means for connecting the operating means to the spool shaft upon movement of the ribbon guide including a key-lever operated vibratory part, a pivoted interponent located between the vibratory part and the operating means and normally disposed out of the path of movement of said part, a bell crank lever 42 pivoted on the frame, a bell crank lever 40 pivoted on the ribbon guide and having one end pivotally connected to bell crank lever 42, a link connecting the interponent and the bell crank lever 42, and a spring connecting said levers for moving the interponent into the path of the vibratory part upon movement of the ribbon guide by the ribbon.

14. Ribbon reversing mechanism for typewriting machines including a frame, a ribbon spool shaft, normally disconnected operating means therefor, a slidable ribbon guide actuated by a projection on the ribbon, and means for connecting the operating means to the spool shaft upon movement of the ribbon guide including a key-lever operated vibratory part, a pivoted interponent located between the vibratory part and the operating means and normally disposed out of the path of movement of said part, a bell crank lever 42 pivoted on the frame, a bell crank lever 40 pivoted on the ribbon guide and having one end pivotally connected to bell crank lever 42, a link connecting the in-

- terponent and the bell crank lever 42, a spring connecting said levers for moving the interponent into the path of the vibratory part upon movement of the ribbon guide by
5 the ribbon, and a spring connected to the frame and to the bell crank lever 42 for returning the parts to their normal positions upon connection between spool shaft and the operating means therefor.
- 10 15. A ribbon reversing mechanism for typewriters comprising in combination, spaced ribbon spool shafts, a spool mounted on each spool shaft to rotate therewith, a longitudinally movable driving shaft normally connected to and disconnected from the respective spool shafts, key operated means for intermittently rotating said shaft, including an oscillatory shaft, a pair of levers for respectively moving the driving
15 20 shaft longitudinally in opposite directions, a pair of actuating arms fixed to said oscillatory shaft, a pair of interponents respectively pivoted on the levers and normally disposed out of the paths of movements of
25 said actuating arms, and ribbon-controlled means associated with the respective spools for positively moving the interponents alternately into positions for engagements by the respective actuating arms.
- 30 In testimony whereof, I have hereunto subscribed my name.

ANTHONY UTZ.
